UNITED STATES PATENT OFFICE

CHARLES WAINWRIGHT, OF ERIE, PENNSYLVANIA.

FLUID-COMPRESSOR.

1,081,175.

Specification of Letters Patent.

Patented Dec. 9, 1913.

Application filed August 28, 1911. Serial No. 646,323.

To all whom it may concern:

Be it known that I, CHARLES WAINWRIGHT, a citizen of the United States, residing at Erie, in the county of Erie and State of Pennsylvania, have invented new and useful Improvements in Fluid-Compressors, of which the following is a specification.

The general object of the invention is to refine in point of compactness, the type of fluid compressor shown in my co-pending application 644,111. And to this end the invention resides in interposing the unloaders between the cylinders and intake box on the low pressure side of the compressor and arranging the said unloaders so as to support the cylinders.

Other objects will appear and be better understood from the following description taken in connection with the accompanying drawings, in which,

Figure 1 is a plan of a multiple-stage compressor which I select for illustrating one adaptation of my invention. Fig. 2 is a side elevation of the compressor shown in Fig. 1 and also showing my improved device applied thereto. Fig. 3 is an end elevation of the parts shown in Figs. 1 and 2. Fig. 4 is a vertical cross section on the line 4—4 of Fig. 2. Fig. 5 is a detail bottom plan of one of the cylinders shown in Figs. 1 to 3 inclusive. Fig. 6 is a detail side elevation of the vacuum breaker. Fig. 7 is a vertical section of the same taken on the line 7—7 of Fig. 6. Fig. 8 is a horizontal section taken on the line 8—8 of Fig. 6. Fig. 9 is a detail vertical section of the unloader.

In the drawings I show a multiple-stage compressor operated by an electric motor. At the outset it may be stated that I do not intend that I shall be limited to employ my invention with this type of compressor neither do I intend that I shall be limited to a compressor operated by the specific form of motor above stated.

In Figs. 1 to 5 inclusive *a* indicates generally, the low pressure cylinders arranged in tandem and *b* the high pressure cylinder. *c* indicates the motor which actuates the piston rods for the cylinders *a* and *b*. One of these rods is shown in Fig. 2 and designated by the numeral 5. The low pressure discharge chambers, one of which is shown in Fig. 4 and designated by 8, are connected with the intercooler 7 and with each other, by piping 6 and the intake chamber (not

shown) of the high pressure cylinder *b* is also connected with the intercooler 7 by piping 9.

10 indicates the intake box chamber and 11 the intake opening.

d indicates generally, the unloaders which may be of any well-known or preferred type, such as choking controllers and which are arranged to connect the intakes of the low pressure cylinders with the intake box chamber 10. In this connection it will be observed, by referring to Figs. 2, 3 and 4, that the intake box chamber 10 forms a support for the low pressure cylinders *a* and the unloaders *d*.

Referring to Figs. 4 and 5, 12, 12 indicate compartments in the intake chamber *e* of each low pressure cylinder *a*. As many of the compartments 12 as desired may be arranged in the intake chamber *e* of each cylinder and when a plurality of cylinders are employed on the low pressure side of the compressor the number of compartments in the various cylinders may or may not be the same. In the present instance, the cylinder to the left in Fig. 2 is provided with two compartments as shown in detail in Figs. 4 and 5, and in this connection it may be stated that the cylinder to the right in Fig. 2 has the same number of compartments and arranged the same as those shown in the cylinder on the left. By virtue of the partition 13 these compartments are out of direct communication with each other and each has its own intake valve (not shown) which controls communication between the cylinder and unloader and which may be of the puppet type and operated by the piston in the cylinder, or mechanically operated.

Any preferred type of unloader may be employed to effect the connection between the compartments 12 and the intake box chamber 10, such as that shown in sectional detail in Fig. 9. Referring now to Fig. 9, the opposite ends of the passage 14 extending through the casing 15 communicates with one of the compartments 12 and the intake box chamber 10. The passage 14 is controlled by a valve 16 which is normally held from its seat 17 by a spring 18 and moved to its seat by compressed air entering the chamber 19, which latter communicates with the chamber 20 in which the head 21 of the valve 16 is arranged to slide.

22 indicates the intake port adapted to be connected by a pipe (not shown) to any de-

sirable point in the pressure line or receiver (not shown).

23 indicates a valve for controlling communication between the port 22 and chamber 19.

5 24 indicates the spring for holding the valve 23 to its seat and 25 the means for adjusting the tension of the spring so that the valve 23 will unseat at a predetermined pressure in the chamber 26 with which the port 22 constantly communicates.

In operation, and assuming that the unloaders are adjusted to operate simultaneously at a predetermined pressure it will be seen that when this pressure is produced in the receiver or pressure system, the valve 23 of each unloader will be unseated, whereupon the air pressure in the chamber 19 will move the valve 16 to its seat, thus cutting off communication between the intake box chamber and compartments 12 of the intake chambers *e*. If it is desired to reduce the volume of air through the intake of the compressor, say one-fourth after a predetermined pressure is obtained in the receiver, and assuming that four unloaders are employed, the valve 23 in one of the unloaders is adjusted so as to operate when the predetermined pressure has been attained in the receiver or compression line. If it is desired to reduce the intake volume to one-half, two of the unloaders are adjusted as above stated and so on. In lieu of the foregoing scheme of adjusting all the unloaders

35 35 may be adjusted so as to operate at different increasing pressures, whereby, to reduce the load on the pistons of the compressor at increasing pressures in the receiver. As an example of this, let it be assumed that the

40 compressor is provided with four unloaders as shown in the drawings, and one of these

has been adjusted to operate at 100 pounds, the second to operate at 96 pounds, the third

45 at 92 pounds and the fourth at 88 pounds.

Now it will be seen that when the pressure in the receiver or pressure line reached 88 pounds number 4 would be cut out, whereupon the volume of the compressor would be reduced one-fourth. When the pressure

50 reached 92 pounds number 3 would be cut out and the load on the pistons reduced and

volume of the compressor likewise reduced to one-half. When 96 pounds

55 was reached number 2 would be cut out, whereupon the volume would be reduced three-fourths and likewise the load on

the pistons. When the pressure reached 100 the compressor would completely unload.

From the foregoing it will have been ob-

60 served that while the reduction in volume and load are being effected, the air is delivered to the compressor at atmospheric pressure, whereby, the device is rendered par-

65 ticularly adapted for altitude service and obviates the usual necessity of wire-drawing or

otherwise lowering the density of air as it enters the compression cylinder or cylinders of an altitude compressor, thus the number of compressions required to maintain a predetermined pressure in the receiver will be reduced and consequently a less amount of motive fluid required to operate the motor, all of which will tend to render the device extremely economical.

Referring now to Figs. 1 and 3 a vacuum breaker *f* is interposed between the high pressure cylinder *b* and intercooler *7* and is adapted to establish communication between the opposite ends of the high pressure cylinder *b* and intercooler *7* when the pistons of the low pressure cylinders are unloaded, whereby, to prevent the creation of a vacuum in the different cylinders and the consequent chattering of the valves thereof.

Figs. 6 to 8 inclusive show the details of the vacuum breaker and referring to these figures it will be seen that the casing *27* is formed with a chamber *28* having a plurality of ports *29* communicating with the interior of the casing. The chamber is also tapped with screw threaded openings *30* corresponding in number to the ports *29*, two of these openings being connected to the opposite ends of the high pressure cylinder by pipes *31* shown in Figs. 1 and 3, the other opening being connected by a pipe *32* with the intercooler *7*.

33 indicates a valve and *34* a circular passage in the body of the valve which aligns with the ports *29* when the valve is lowered as shown in Fig. 7.

35 35 indicates a plunger suitably connected to the lower end of the valve *33* and extending part way into a chamber *36* at the lower end of the casing *27* and having a reduced stem *38* to bear on the bottom of the chamber, whereby, to hold the parts in the positions shown in Fig. 7.

39 indicates an opening tapped into the chamber *36* and *40* a pipe connecting the chamber *36* with the intercooler *7* as shown in Fig. 8.

41 indicates a pin screwed through a cross bar *42* bearing on the upper end of the casing *27*, and *43* indicate retractile springs connecting the cross bar *42* with arms *44* extending from any convenient portion of the casing *27*. The springs are tensioned by turning the head *45* of the pin in the required direction, whereby, the valve *33* may be adjusted to lift at predetermined pressures and lowered to the position shown in Fig. 7 when the pressure in the intercooler falls below a predetermined point.

Ordinarily the valve will be adjusted to 125 lift when the pressure in the intercooler is a trifle above that of the atmosphere, the said valve being actuated to do so by the pressure in the pipe *40*. When the valve is lifted the ports *20* of the chamber will 130

be blanked by the lower portion of the valve so that the air compressed by the low pressure pistons after moving from the intercooler, will pass through the pipe 9 and into the high pressure cylinder *b* and from thence through the pipe 45 to the receiver (not shown). When the last load remover goes into operation the pressure in the intercooler will have fallen to substantially that of the atmosphere, whereupon the springs 43 will move the valve 33 downwardly, whereby, communication will be established between the opposite ends of the high pressure cylinder and intercooler, for the purpose before stated.

It will be observed that when the pressure in the intercooler falls sufficiently to release one of the unloaders previously operated the spring 24 will force the valve 23 to its seat, whereupon the compressed air in the chamber 19 will escape through a choked passage 46 communicating with the chamber 19 and atmosphere.

From the foregoing it will be seen that the presence of the vacuum breaker is not essential to the successful operation of the unloaders, nevertheless, the inclusion of this element in the combination produces a more refined compressor structure. It may be further stated that although I do not show the high pressure cylinder equipped with a plurality of unloaders, nevertheless, the structure shown for the low pressure cylinder may, if desired, be embodied in the high pressure.

Although I have shown and described one embodiment of my invention it is to be understood that I am not to be limited to the specific structure and arrangement of parts since various changes will be made, within the scope of the appended claims without departing from the spirit or sacrificing any of the advantages of the invention.

What I claim as new is:

1. In a fluid compressor, the combination of a cylinder adapted to discharge into a container and having an intake chamber divided into a plurality of compartments, and an unloader connected with each of said compartments and controlled by the container pressure for the purpose described.
2. In a fluid compressor, the combination of a cylinder adapted to discharge into a container and having an intake chamber

divided into a plurality of compartments, and a plurality of unloaders controlled by the container pressure and connected to the compartments of the cylinder and adjustable so as to operate successively at predetermined increasing pressures in the container.

3. In a multiple-stage fluid compressor, the combination with the low and high pressure cylinders, the intake chamber of one of which is divided into a plurality of compartments; of a plurality of unloaders controlled by the final pressure and connected with the said compartments.

4. In a multiple-stage fluid compressor, the combination with the low and high pressure cylinders, the intake chamber of one of which is divided into a plurality of compartments; of a plurality of unloaders controlled by the final pressure and connected with the compartments and adjustable so as to operate successively at predetermined increasing pressures.

5. In a fluid compressor, the combination of an intake box, a fluid-operated unloader superimposed on the said intake box, and an opening at one end into the box, and a cylinder superimposed on the unloader and having its intake in communication with the unloader.

6. In a fluid compressor, the combination of an intake box, a plurality of fluid operated unloaders superimposed on the intake box and opening at one end into the box, and a cylinder superimposed on the unloaders and having an intake chamber divided into a plurality of compartments arranged so as to communicate with the unloaders.

7. A double-acting fluid compressor, the combination of an intake box, a plurality of cylinders having intake chambers divided into a plurality of compartments and arranged above the intake box, and a plurality of fluid actuated unloaders interposed between the cylinders and the intake box and connected to the intakes of the cylinders at one end and arranged for controlling communication between the intakes of the cylinders and the intake box.

In testimony whereof I affix my signature in presence of two witnesses.

CHARLES WAINWRIGHT.
